[57] CLAIM

The ornamental design for a portable remote lighting
control transmitter design as shown and described.

DESCRIPTION

FIG. 1 is a top, front and left side perspective view of a
portable remote lighting control transmitter showing
my new design;
FIG. 2 is a front elevational view thereof;
FIG. 3 is a right side elevational view thereof, the left
side being a mirror image;
FIG. 4 is a rear elevational view thereof; and
FIG. 5 is a bottom plan view thereof.

FIG. 1

FIG. 2

FIG. 3

FIG. 4

FIG. 5
